CLAIM

The ornamental design for a spoiler for motor vehicle, as shown and described.

DESCRIPTION

FIG. 1 is a front perspective view of the spoiler for motor vehicle, showing the new design;

FIG. 2 is a front elevational view of the spoiler for motor vehicle thereof;

FIG. 3 is a rear elevational view of the spoiler for motor vehicle thereof;

FIG. 4 is a right side elevational view of the spoiler for motor vehicle thereof;

FIG. 5 is a top plan view of the spoiler for motor vehicle thereof;

FIG. 6 is a bottom plan view of the spoiler for motor vehicle thereof; and,

FIG. 7 is an environmental view of the spoiler for motor vehicle thereof.

The left side elevational view of the spoiler for motor vehicle is a mirror image of the right side elevational view of the spoiler for motor vehicle shown in FIG. 5.

The broken lines in the drawings illustrate environmental subject matter and form no part of the claimed design.
